UNITED STATES PATENT OFFICE.

LUTHER C. CROWELL, OF BROOKLYN, ASSIGNOR TO R. HOE & CO., OF NEW YORK, N. Y.

SHEET-DELIVERY APPARATUS.

SPECIFICATION forming part of Letters Patent No. 339,532, dated April 6, 1886.

Application filed October 28, 1885. Serial No. 181,125. (No model.)

To all whom it may concern:

Be it known that I, LUTHER C. CROWELL, a citizen of the United States, residing at Brooklyn, county of Kings, and State of New York, have invented certain new and useful Improvements in Sheet-Delivery Apparatus, fully described and represented in the following specification, and the accompanying drawings, forming a part of the same.

10 This invention relates to a delivery mechanism of that class which is adapted to operate upon a continuous web to sever the same into short lengths or sheets, fold said sheets to convenient dimensions for handling, and, if desired, deliver the folded product divided into lots containing any desired number.

15 It is the especial object of the invention to provide a mechanism of this character which shall be capacitated to deliver products of various sizes or volumes so as to meet the wants of those publishers who issue papers which vary in size with the different days of the week.

20 To this end the invention consists, principally, in a novel organization of mechanisms by which this result is effected in a simple and economical manner.

25 The invention also includes an organization of mechanisms by which the product may be delivered folded to different dimensions, or by which, when desired, it may be delivered in a flat or unfolded condition.

30 The invention also includes various improvements in certain of the individual mechanisms of which the complete delivery mechanism is composed.

35 As a full understanding of the invention can be best imparted by a detailed description of the construction, organization, and operation of the mechanisms in which it is shown as embodied, in the present case such description will be first given, after which some of the modifications which may be made in the construction and organization without departing from the invention will be pointed out.

40 A delivering mechanism embodying the present invention in its most complete and desirable form consists of a web-turning or turning and associating mechanism consisting of suitably-arranged turning-bars; a primary folding mechanism consisting of one or more longitudinal folders, to which the web or webs pass

from the turning or turning and associating mechanism; a severing mechanism by which the web or webs are severed into sheets, and which is arranged to receive the web or webs 55 either direct from the printing mechanism or from the primary folding mechanism; a secondary or final folding mechanism, which is also a sheet-associating mechanism, and which is arranged to impart a transverse fold to each 60 sheet separately, or to associate the sheets in pairs and impart a transverse fold to the associated pairs, or to permit the sheets to pass without being either folded or associated; a piling mechanism which is arranged to receive 65 the folded sheets from the final folding mechanism and pile them in proper shape for removal; a sheet-collecting mechanism which is arranged to receive the sheets from the final folding mechanism and collect them into lots containing any desired number, and a second piling mechanism which is arranged to receive the 70 collected lots of sheets and pile them.

The organization thus briefly outlined will now be described in detail, reference being had 75 to the accompanying drawings, in which—

Figure 1 is an elevation, partly in section, of a delivery mechanism embodying the present invention, showing also a diagrammatic view of an ordinary form of web-printing 80 mechanism. Fig. 2 is a plan view of the delivery mechanism, showing particularly the web-turning or turning and associating mechanism. Fig. 3 is a sectional elevation of the same, taken upon the line $\alpha\alpha$ of Figs. 1 and 2. 85 Fig. 4 is an enlarged sectional elevation of the final folding mechanism, and also of the severing and sheet associating and collecting mechanisms and the sheet-piling mechanisms. Fig. 5 is a side elevation, partly in section upon a 90 like scale, of the mechanism for collecting a number of sheets when it is desired to deliver the sheets in an unfolded condition or without the final fold. Fig. 6 is a sectional elevation, upon a still more enlarged scale, of the final 95 folding mechanism and of the severing and sheet-associating mechanism. Figs. 7 and 8 are details showing the means for operating the sheet-holding pins and the strippers of the sheet-associating mechanism. Figs. 9 and 10 100 are enlarged cross-sections of the cylinder forming the sheet-collecting mechanism for

collecting the sheets into lots when they are to be delivered in an unfolded condition or without the final fold. Fig. 11 is a view showing the means for operating the sheet-holding pins of the folding mechanism and the strippers of the collecting mechanism. Figs. 12 and 13 are views similar to Figs. 4 and 5, illustrating a modified construction, which will be herein-after explained. Fig. 14 is a cross-section of the severing, folding, and associating mechanisms, illustrating another modified construction, which will also be herein-after explained. Fig. 15 is a plan view of the same. Fig. 16 is a plan view of the delivery mechanism, showing a modified arrangement of the web-turning or turning and associating mechanism. Fig. 17 is an elevation of the same. Fig. 18 is a view similar to Fig. 16, showing another modified arrangement of the same mechanism. Fig. 19 is an elevation of the same; and Figs. 20 and 21 illustrate details, which will be herein-after referred to. Fig. 22 is a partial front elevation of the fly for delivering the sheets from the collecting mechanism, showing particularly the guides, which are located between the fingers of the fly.

In many of these figures the frame-work for supporting the various parts is partly or wholly omitted, in order to more clearly show the other parts.

Referring to said drawings, it is to be understood that the printing mechanism therein shown is of an ordinary form of web-perfecting mechanism, consisting, essentially, of two form-cylinders, 95 97, two impression-cylinders, 96 98, and suitable inking mechanisms, as 101. This mechanism, as herein shown, is capacitated to perfect a double-width web—that is to say, a web which is of sufficient width to receive two or more printed pages abreast or widthwise, so that, being properly printed, it can be split longitudinally to produce duplicate side-by-side small products, or after being split can have its longitudinal sections associated to form products of larger volume. The web A led from the roll 100 passes around the usual leading-rolls, 99, and through the printing mechanism by which it is perfected, after which it passes to conductors, by which it is directed to the delivery mechanism.

It is to be remarked that the printing mechanism thus briefly described forms no part of the present invention, but has been illustrated simply for the purpose of aiding in a ready understanding of the delivery mechanism. The printing mechanism may therefore be of any approved form, and may, as will herein-after appear, be capacitated to perfect either a single, double, or greater width web.

The conductors by which the web is directed from the printing mechanism to the delivery mechanism consist of three series of tapes, 50, 52, and *i*, two series of stationary guides, 51 and 9, and a series of switches, 18. The series of tapes 50 pass around pulleys 53, thence upward around a roll, 54, and forward over a roll, 55, and above and in contact with

the upper surfaces of the bars 10 12, forming the web turning and associating mechanism, and return around pulleys 56 57 58. The series of tapes 52 pass around a roll, 59, located beneath the roll 54, and thence upward with the tapes 50, and return around the roll 55. The series of tapes *i* are stretched around the roll 55, and a roll, 24, forming one of the fold-laying rolls of the primary folding mechanism. The guides 51 bridge the space between the cylinder 96 and the roll 59 and contact with the tapes 50. The guides 9 extend from the bars 10 12 to a point near the roll 55, 80 and also contact with the tapes 50. The switches 18 bridge the space between the roll 55 and the ends of the guides 9. The web A, after being perfected, as stated, and as it emerges from between the cylinders 95 96, has its leading end entered between the tapes 50 and guides 51. The tapes 50 then act to conduct the end of the web forward and enter it into the bite of the tapes 50 52, by which tapes it is then carried upward to and over the roll 55, 90 in passing which roll it is split longitudinally into two sections, *a b*, which in the subsequent operations will be termed "webs," by a slitter, 49, which is arranged and operates in the usual manner. The webs *a b* are then conducted forward by the tapes 50 and the guides 9 to the bars 10 12, forming the web turning and associating mechanism. The conductors just described are not essential, but they perform a useful function in threading the machine and also in supporting the web in its passage to the delivery mechanism.

The web-turning or turning and associating mechanism consists, as already stated, of two turning-bars, 10 12. These bars, as shown in Figs. 2 and 3, are arranged at right angles to each other and in such position that the apex formed at their point of intersection points toward the slitter 49, and is at the center of the web and coincides with the line of division between the two narrow webs *a b*. The bars 10 12 are supported at their apex or point of union and at their outer ends by brackets 6 8, resting upon the frame-work. The brackets 8 are connected together by a tie-bar, 11, that lies upon the inner side of the frame-work, and is provided centrally of its length with a nut that is engaged by an adjusting-screw, 17, held in bearings in the frame-work and provided with a hand-wheel, by which it may be operated. The brackets are each secured to the frame-work by bolts passing through slots therein, which serve to hold the turning-bars in proper position and guide them in their adjustment. The turning-bars 10 12 are made adjustable in this manner, so that their positions may be changed with respect to the longitudinal folders forming the primary folding mechanism, the object being to permit the web A, and consequently the webs *a b*, to be varied in width, within certain limits, and yet cause the webs *a b* to be presented to the longitudinal folders in such position that they will be folded centrally. This feature, how-

ever, forms no part of the present invention, as it is claimed in my prior application for Letters Patent filed March 28, 1885, Serial No. 160,436.

5 The turning-bars 10 12 are provided with curved guides 19, which are supported in any suitable manner and operate to direct the leading ends of the webs around the bars in the manner shown and described in my 10 application for Letters Patent filed June 17, 1885, Serial No. 168,924. These guides are not herein claimed, however, as they are claimed in said application. The guides 19 are provided with extensions 28, which extend laterally from the bars and serve to support the webs as they are led from the bars to a pair of leading-rolls, 44 48, located at the opposite sides of the machine. From the rolls 44 48 the webs *a b* are led inward around a pair 15 of adjustable register rolls, 45 47, and thence outward, as best shown in Fig. 3, over a pair of rolls, 42 46, located at the bases of a pair of longitudinal folders, 20 21, which form the primary folding mechanism. These folders 20 25 may be of any well-known form. As herein shown, however, they are of substantially the construction shown, described, and claimed in my application for Letters Patent filed February 8, 1884, Serial No. 120,116, to which 30 reference may be had for a detailed description thereof.

As shown in Figs. 1 to 3, the folders 20 21 are pivotally secured at their bases to bosses projecting from the frame-work through supporting arms which are capable of oscillation on said bosses. These bosses are concentric with the shafts of the rolls 46 42, through which bosses said shafts pass and find bearings therein. By thus supporting the bases 35 of the folders their surfaces are always presented in a true tangential line from said rolls 46 42 in any adjustment of their apexes by the rods 71. The longitudinal folders thus supported are arranged with respect to each 40 other so that their bases at the rolls 46 42 are parallel while their apexes point outward in opposite directions, and are each provided with external turners formed by the pairs of rolls 22 and 23, and with the single pair of 45 fold-laying rolls 24 25, all of which find suitable bearings in the frame-work.

It is to be observed that the rolls 24 25 lie parallel with the printing-cylinders, and also that they co-operate with both of the folders 50 20 21, and also that they are of sufficient length to receive both of the webs *a b* side by side when they are in an unfolded condition. The purpose of this is to permit the webs, when desired, to be led directly from the roll 55 to 55 the severing and secondary folding mechanism, instead of passing to the primary folding mechanism, as will hereinafter more fully appear.

After leaving the rolls 24 25, the webs, either 60 unfolded or longitudinally folded, pass side by side into the control of a pair of cylinders, 30 31, which are of sufficient length to receive

the webs in an unfolded condition, and which, together with their auxiliary devices, form the severing and the folding and associating mech- 7c anisms, before referred to.

Referring now particularly to Figs. 4 to 8 and 11, the organization of these mechanisms will be described. The cylinder 30, which, as here shown, is of a circumference equal to the 75 length of two sheets, is provided at opposite points with cutting-grooves 4, and the cylinder 31, which is of like size, is provided with ordinary severing-blades, 5, which are arranged to co operate with the grooves 4 in the usual 80 manner. The cylinder 30 is provided just in the rear of the grooves 4 with sets of impaling-pins 3 3', which are mounted upon arms extending from rock-shafts 29, journaled in the cylinder and are arranged to be protruded 85 and retracted through openings in the cylinder in the usual manner. The pins are protruded by means of springs, (not shown,) and the shafts 29 are provided with arms 43, which, as the cylinder revolves, are engaged by a stationary cam, 77, (see Figs. 5 and 11,) so as to rock the shafts and cause the pins to be retracted to release the sheets at the proper point. The cylinder 30 is also provided at the proper points between the sets of pins with 90 two ordinary rotating folding-blades, 2, which are operated by means of a cam, (not shown,) in the usual manner, to fold the sheets off the cylinder and into the bite of a pair of folding-rolls, 13 14, from which rolls the sheets pass 95 to the piling mechanism.

The parts just described constitute the severing mechanism and the secondary folding mechanism, before referred to.

The cylinder 31 is provided, just in the rear 105 of one of the blades 5, with a set of impaling-pins, 80, which are mounted upon arms extending from a rock-shaft, which is journaled in the cylinder and is provided with an arm, 81, (see Figs. 7 and 8,) by which it can be rocked 110 to and secured in position to keep the pins either protruded beyond or retracted within the cylinder, according as it is desired to associate sheets or not. The pins 80 are provided with corresponding stripper-fingers, 82, which 115 are mounted upon a rock-shaft, 78, which is journaled in the cylinder, and is provided with an arm, 83, which, as the cylinder revolves, engages with a stationary cam, 86, (see Figs. 7 and 8,) and is thereby operated so as to rock 120 the shaft 78 and cause the fingers 82 to strip the leading ends of the sheets from the pins 80 and direct them into a pathway by which they are re-presented to the cylinder 30 in position to be associated with the next following 125 sheets, so that the two will be folded together between the rolls 13 14, all as will be more fully explained when the operation of the mechanism is described. The stripper-fingers 82 are held in their normal position close 130 against the surface of the cylinder by means of a spring or springs, (not shown,) and the cam 86 is supported upon rods 79, which are made adjustable in the frame-work by means

of a screw, 93, so that when sheets are not to be associated the cam may be moved out of the path of the arm 83, and thus prevent the stripper-fingers from being operated.

5 The pathway into which the sheets are directed by the fingers 82 is formed of two series of tapes, 84 88, and two series of guides, 91 92, as best shown in Figs. 4 and 6. The tapes 84 pass around pulleys 85 87, and run in close proximity to the lower side of the cylinder 31, while the tapes 88 pass around pulleys 89 at the side of the pulleys 87; thence under pulleys 87 and around pulleys 90, located in close proximity to the cylinder 30; thence for a short distance in contact with said cylinder, and thence around the roll 14 and back to the pulleys 89. The guides 92 bridge the space between the pulleys 85 and the cylinder 30, and co-operate with the tapes 88, and the guides 91 bridge the space between the pulleys 89 and the cylinder 31, and co-operate with the tapes 84.

The parts just described form the sheet associating mechanism, before referred to.

25 As the folded sheets emerge from the folding-rolls 13 14, they are projected between guides 94, and as they are released from the folding-rolls they pass into the control of two series of tapes, 15 16, by which they are conveyed to the piling mechanism, which co-operates with the final folding mechanism to pile the folded sheets. This piling mechanism, as herein shown, is of substantially the character as that shown and described in my former Letters Patent, No. 281,754, and consists of a rotating cylinder or carrier, 32, which is provided with sheet-grasping devices, which are arranged to grasp the leading ends of the sheets, carry them forward, and deposit them against stops 42 and upon a slowly-moving apron or series of belts, 41, which pass around rolls, as 38 39, and by which the sheets are conveyed away from the machine. The stops 42 will preferably be provided with mechanism such as shown and described in my application for Letters Patent filed October 6, 1884, Serial No. 144,808, by which the folded sheets will be piled irregularly, so that they can be divided into lots containing some predetermined number without the necessity of counting.

55 The tapes 15 pass around pulleys 33, located a short distance below the roll 13, thence downward beneath pulleys 36, and upward around the carrier 32, returning around pulleys 34. The tapes 16 pass around pulleys 35, located by the side of the pulleys 33, thence downward around the pulleys 36, thence upward, running for a short distance in contact with the carrier 32, and returning around pulleys 37. It will be observed that the pulleys 33 35 are placed a short distance apart, so as to prevent the tapes 15 16 from coming into close biting contact until they arrive at the pulleys 36. This permits the folded sheets to be projected downward between the tapes for some distance before they actually come under

the control of the tapes, thus preventing the sheets from wrinkling or buckling in passing from the control of the rolls 13 14 to the control of the tapes, when, as is usually the case, the latter and the carrier 32 are run at a reduced speed.

70 The sheet-collecting mechanism, by which the sheets may be collected into lots to be delivered in an unfolded condition or with only the longitudinal fold, consists, essentially, of a cylinder, 60, which is arranged at the side of and a short distance from the cylinder 30, and is of the same length as the cylinders 30 80 31. As herein shown, this cylinder 60 is of a circumference equal to or slightly more than the length of one sheet.

75 Referring now particularly to Figs. 4, 5, 9, 10, and 11, the construction and organization of this collecting mechanism will be described. The cylinder 60 is provided around its circumference with a number of yielding pieces, *c*, which have the effect of enlarging the circumference of the cylinder, as shown in Fig. 9, but also permit the cylinder to be gradually contracted in diameter as the sheets are accumulated upon its surface, as shown in Fig. 10. The yielding pieces *c*, as shown in the present case, consist of curved spring-plates, which 95 are secured at one end to the cylinder, and have their free ends bent inward and extended into openings in the cylinder. The ends of the pieces *c* which enter the openings in the cylinder are provided with projections, which engage with studs or pins *o*, and thus limit the outward movement of the pieces *c*, as best shown in Fig. 9. The construction and arrangement of the pieces *c* may be considerably varied without departing from the principle 105 of the invention. For example, they might consist of spring-seated pieces extending lengthwise of the cylinder, or the cylinder might be made in sections, so as to be capable of expanding and then contracting as the sheets 110 accumulate upon it. The cylinder 60 is also provided with a set of impaling-pins, *d*, which are mounted upon a shaft which is journaled in the cylinder, so as to have a slight rocking movement. The pins *d* are so positioned and project such a distance beyond the cylinder that when the cylinder is in operation the leading ends of the sheets, held by the pins 3 3' of the cylinder 30, will, as the latter pins are retracted, be impaled by 120 the pins *d* and transferred from the cylinder 30 to the collecting-cylinder 60. The cylinder 60 is also provided with two series of co-operating stationary guides, *e r*, which are supported upon suitable rods and are arranged to nearly surround the cylinder, and thus act to hold the sheets onto the surface of the cylinder, as shown in Fig. 10. The cylinder 60 is also provided with a series of stripping-fingers, *n*, which are mounted upon a rock-shaft journaled in the cylinder, and are arranged to normally lie within or upon the surface of the cylinder, and are provided with slots, through 130 which the pins *d* project. The fingers *n* are

provided with means by which they are rocked outward at predetermined times, so as to strip the accumulated sheets from the pins *d* and guide their leading ends off the cylinder and 5 into a pathway formed by the portions *f* of the guides *e r*. This operation of the stripping-fingers is effected as follows: The shaft upon which the fingers are mounted is provided with an arm, *m*, having a stud or bowl which 10 travels in the groove of a stationary cam, 63. (See Figs. 5 and 9.) The bowl of the arm *m* normally travels in a path concentric with the periphery of the cylinder 60; but the cam 63 is provided with a vibrating switch, 64, which 15 is periodically operated, so as to cause the bowl to pass inward and travel along a surface, as *s*, (see Figs. 11 and 20,) for a short distance, and thus rock the arm *m* and raise the fingers *n*, so as to strip the sheets off the pins *d* and 20 direct them between the guides *f*, as shown in Fig. 10. The switch 64 is operated as follows: The switch is mounted upon a short shaft, *t*, (see Figs. 20 and 21,) which extends through 25 the cam 63, and is provided with an arm, *k*, which is connected to an arm, 66, which is forked at its end and straddles a stud extending from the frame-work. (See Figs. 5, 20, and 21.) This stud carries a loosely-mounted gear, 67, in the face of which is formed a cam-groove, 65, into which extends a stud projecting from the arm 66. The gear 67 engages 30 with a gear, 68, (see dotted lines in Fig. 9,) which is mounted upon the shaft of the cylinder 60. The cam-groove 65 is so formed that 35 the switch 64 will be rocked at each revolution of the gear 67, but the gears 67 68 are so proportioned that the bowl of the arm *m* will not be in position to be directed inward by the switch at the time the switch is rocked, 40 except at the end of each tenth revolution, thereby allowing ten sheets to be accumulated upon the cylinder 60 between each two vibrations of the fingers *n*.

Although the means as just described for 45 operating the stripping-fingers forms a practical arrangement for so doing, any other well-known means may be employed, as well as different sized and proportioned gears, to cause the cylinder to accumulate a greater or less 50 number of sheets.

As the accumulated sheets emerge from between the guides *f*, they pass in front of an ordinary fly, 61, by which they are piled upon a table, 62. This table may, and preferably 55 will, be provided with the well-known means by which it is shifted at regular intervals, so as to produce irregularities in the pile of sheets, and thus enable them to be separated into lots containing any desired number without the 60 necessity of counting.

The fly 61 is operated by any of the well-known means for that purpose, and there are preferably provided stationary guides, as 76, (see Figs. 4 and 22,) which lie between the 65 fingers of the fly, and against which the sheets will rest as they pass downward in front of the fly. The sheets from the fly, instead of being

deposited upon a table, as 62, may be deposited upon a slowly-moving apron or series of belts, and in such case the irregularity in the pile caused by the movement of the apron or belts will effect the counting.

In order to prevent a lot of accumulated sheets from falling suddenly as soon as released from the cylinder 60, and thus becoming disarranged, there are provided a pair of slowly-moving segmental rolls, 69 70, between which the lot of sheets passes as it emerges from the guides *f*. These rolls are cut away for the greater portion of their circumference or made 80 segmental, so as to permit the lot of sheets to pass freely between them until their full portions come together, when the rolls will nip the lot of sheets and feed it slowly downward in front of the fly. The rolls 69 70 are geared 85 together by gears 74 75, and are driven from the gear 72 through an intermediate, 73, which is of suitable size to properly time the rolls 69 70.

The various other moving parts of the mechanism herein described are provided with suitable engaging-gears, by which the several parts are properly timed with relation to each other.

The cylinder 60 and the fly 61, and also the 95 carrier 32 and its tapes and the apron or belts 41, will be driven in such manner that they can be thrown out of operation when desired.

The gears for driving the various parts are not herein shown, because they can be readily 100 supplied by any ordinarily skillful mechanic.

The remaining features of construction will be described in connection with the description of the operation of the mechanism.

The delivery mechanism, organized as herein shown and described, is capacitated to deliver the printed product in the following forms and conditions—viz: In the form of single full sheets, either in an unfolded condition or folded once longitudinally and once transversely, or once transversely; in the form of pairs of full sheets associated together and folded, as above; in the form of four full sheets, said sheets being first associated in pairs and folded longitudinally and the pairs 115 associated and folded transversely; in the form of a single full sheet and a single half-sheet associated together and folded once longitudinally, or once longitudinally and once transversely; in the form of two full sheets 120 and two half-sheets, the full and half sheets being first associated in pairs and folded longitudinally, and the pairs then associated and folded transversely; or in the form of half-sheets in an unfolded condition or folded once 125 transversely.

To deliver single full sheets in an unfolded condition, the arm 81 will be shifted to the position shown by dotted lines in Fig. 7, so as to retract the pins 80, and the cam 86 will also 130 preferably be moved outward, so as to not engage the arm 83, thus rendering the fingers 82 idle. The blades 2 and the carrier 32 will also be rendered idle, and the collecting-cylinder

60 and fly 61 will be thrown into operation, and the switches 18 will be turned and secured in the position shown by dotted lines in Fig. 1. The web A will be split by the slitter 49, and 5 the two sections or narrow webs *a b*, instead of passing forward to the turning-bars 10 12, will pass downward along the tapes *i*, as shown by dotted lines in Fig. 1, and be entered side by side between the rolls 24 25 and the cylinders 30 31, where their leading ends will be impaled by one set of the pins 3 or 3^a, and carried around upon the cylinder 30. As the cylinders 30 31 complete a half-revolution one of the blades 5, co-operating with the corresponding groove, 4, will sever the webs, and their freshly-severed ends will be impaled by the other set of the pins 3 or 3^a. At or about the same time that this takes place the pins upon which the leading ends of the now severed sheets are impaled will be retracted by the cam 77, and at the same time the pins *d* of the cylinder 60 will impale the leading ends of the sheets and take them off the cylinder 30 and onto the cylinder 60. At the end of 25 the next half-revolution of the cylinders 30 31 another pair of sheets will be severed from the webs *a b*, and these sheets will in like manner be taken by the pins *d* and carried onto the cylinder 60 on top of the sheets 30 already there, and so the operation will continue to be repeated until the proper number of sheets has been accumulated upon the cylinder 60, when the fingers *n* will be operated, as already described, to strip the accumulated 35 lot of sheets off the pins *d* and direct them to the fly 61, by which they will be piled upon the table 62.

To deliver single full sheets with one longitudinal fold, the adjustment of the mechanisms 40 will be the same, except that the switches 18 will be turned down to the position shown in Fig. 1. The webs *a b* will then, instead of passing downward along the tapes *i*, pass forward between the tapes 50 and guides 9 to the 45 turning-bars 10 12, around which bars they will be directed by the guides 19, as shown in Fig. 2, after which they will pass around their respective rolls 48 47 46 and 44 45 42 to their respective longitudinal folders 20 21, in passing 50 which folders they will be folded longitudinally, as shown in Fig. 3. After leaving the folders 20 21, the now folded webs will pass between the rolls 24 25 and enter side by side between the cylinders 30 31, after which the 55 operation is exactly the same as already described, except that the sheets, instead of being delivered in an unfolded condition, are folded once longitudinally.

To deliver single full sheets with one longitudinal and one transverse fold, the folding-blades 2 of the cylinder 30 will be rendered operative, the cylinder 60 and fly 61 will be thrown out of operation, and the carrier 32 will be thrown into operation. The webs *a b* 65 will be folded longitudinally, the same as just described, but the longitudinally-folded sheets, instead of being taken by the pins *d* of the

cylinder 60, will, when released from the pins of the cylinder 30, be folded off the cylinder by the blades 2 into the bite of the rolls 13 14, 70 from which rolls they will be carried by the tapes 15 16 to the carrier 32 and be piled upon the belts 41.

To deliver single full sheets folded once transversely, the adjustment of the mechanisms 75 will remain the same as last described, except that the switches 18 will be turned up to the position shown by dotted lines in Fig. 1. The operation will be the same as last described, except that the webs *a b*, instead of passing 80 forward to the turning-bars 10 12, will pass downward along the tapes *i* to the rolls 24 25.

To deliver pairs of full sheets folded either once longitudinally or once longitudinally and once transversely, the adjustments and operations will be respectively the same as in delivering a single sheet folded to the same dimensions, except that the web *b*, instead of passing from the roll 45 to the roll 42 and folder 21, will be led around an adjustable 90 register-roll, 102, and thence over the roll 46 onto the folder 20, so as to be brought under and associated with the web *a*, as shown by dotted lines in Fig. 3.

To deliver pairs of full sheets associated 95 and folded once transversely, the pins 3^a will be retracted within the cylinder 30, and secured in that position, the pins 80 will be protruded beyond the periphery of the cylinder 31, as shown in Figs. 6 and 7, the cam 86 will 100 be moved inward, so as to operate the fingers 82, as shown in Fig. 8, and the switches 18 will be turned up to the position shown by dotted lines in Fig. 1. The webs *a b*, instead of passing forward to the turning-bars 10 12, 105 will pass downward along the tapes *i* and be entered between the cylinders 30 31, in position to be taken by the pins 80 and carried around upon the cylinder 31. As the leading ends of the webs arrive at a point above the 110 pulleys 87, the fingers 82 will be operated by the cam 86, as shown in Fig. 6, so as to strip the ends of the webs from the pins and direct them into the pathway formed by the tapes 84 88 and guides 91 92. When the cylinders 115 30 31 have completed one-half a revolution, the webs will be severed, and the freshly-severed ends will be taken by the pins 3 and carried forward upon the cylinder 30. The 120 sheets which were directed off the cylinder 31 120 will in the meantime be carried forward by the tapes 84 88, and will have their leading ends presented to the cylinder 30 at the roll 90 just in time to join with the leading ends of the webs held by the pins 3, so as to be 125 taken by said pins, and thus become associated with the second pair of sheets severed from the webs. The pairs of sheets thus associated will at the proper time be released by the pins 3, and folded off the cylinder 30 by one of the 130 blades 2. The pairs of sheets thus associated and folded will then pass to the carrier 32, and be delivered the same as already described.

To deliver four full sheets associated and folded as hereinbefore stated, the adjustment and operation will be the same as in delivering a two-sheet product folded to like dimensions, except that the pins 3^a will be made inoperative and the pins 80 and fingers 82 will be made operative.

To deliver one full and one half sheet associated and folded either once longitudinally or once longitudinally and once transversely, the adjustments and operations will be respectively the same as in delivering two full sheets folded to like dimensions, except that the web b will be of only half-width.

15 To deliver two full and two half sheets associated and folded as hereinbefore stated, the adjustment and operation will be the same as in delivering four full sheets folded to the same dimensions, except that the web b will be of only half-width.

20 To deliver half sheets either in an unfolded condition or folded once transversely, the adjustments and operations will be respectively the same as in delivering single full sheets in 25 the same conditions, except that the slitters 103 (see dotted lines in Fig. 2) will be put into operation, so that the webs a and b will be each split longitudinally.

In those cases where two sheets are associated and then folded longitudinally, it will be desirable to have the sheets pasted together along the line of the longitudinal fold. This can readily be done by providing a pasting apparatus, as 104, (see Fig. 3,) by which a 30 line of paste will be applied to the longitudinal fold-line of the web a as it passes the roll 47. In those cases where pasting is not required the pasting apparatus will be thrown out of operation.

40 If desired, the full sheets may be split on the line of the longitudinal fold by means of slitters, as 105, located as shown by dotted lines in Fig. 3, or in any other suitable position.

45 The mechanisms constructed and organized in the manner hereinbefore described embody the invention in what I regard as the most complete and desirable form.

The arrangement or organization of the 50 mechanisms, and also the construction of many of them, may be varied considerably without departing from some of the principal features of the invention.

The turning-bars 10 12, forming the web- 55 turning or turning and associating mechanism, instead of being arranged as shown in Figs. 1, 2, and 3, may be reversed in position, as shown in Figs. 16 and 17; or the bars, instead of being arranged at right angles to each 60 other, may be arranged parallel to each other, as shown in Figs. 18 and 19; or the web-turning or turning and associating mechanism may be arranged in any other suitable manner to accomplish the necessary result. So, also, the 65 folders 20 21, instead of being so arranged that their apexes point in opposite directions, may

be arranged to point in the same direction, as shown in Figs. 18 and 19.

One of the folders 20 or 21 may be omitted; but in such case a single instead of a double 70 width web will be used when it is desired to deliver single full sheets folded longitudinally.

So, also, the whole mechanism, instead of being capacitated to operate upon a double-width web, may be only capacitated to operate 75 upon a single-width web. In such case of course two sheets could not be associated and folded longitudinally.

The secondary or transverse folding mechanism, or both this mechanism and the severing mechanism, instead of being parallel with, may be at right angles to, the printing-cylinders. In such cases the turning bar or bars 10 12 may be arranged to act upon the web or webs after it or they pass the longitudinal 85 folder or folders; or the bar or bars may be arranged to turn the web or webs to present it or them to the severing and transverse folding mechanisms, instead of to the longitudinal folder or folders; or even when the transverse 90 folding mechanism is parallel with the printing-cylinders the turning bar or bars may be arranged after instead of before the longitudinal folder or folders.

The transverse severing and folding mechanisms, and also the sheet-associating mechanism, may be of a different form from those shown without departing from the principal features of the invention. For example, these mechanisms may be organized as shown in 100 Letters Patent No. 317,740, and as illustrated in Figs. 14 and 15. In this case the fingers 82 and the pathway formed by the tapes 84 88 and guides 91 92 are dispensed with, and the cylinder 31 is of a circumference equal to the 105 length of only one full sheet, and is as a consequence provided with only one blade 5, and the pins 80, instead of being held stationary either in their protruded or retracted position, are held in a protruded position by means of 110 a spring, and are retracted to release the sheets by means of a cam, w, carried upon the cylinder 30, and which engages with a stud upon the arm 87 in the same manner as in the Letters Patent referred to. When sheets are to 115 be associated, the pins 3^a will be rendered inoperative and the pins 80 operative. The first sheet will be taken by the pins 80 and carried around upon the cylinder 31, and at the end of the first revolution of the cylinder 31 the 120 pins 80 will be retracted by the cam w, so that the sheet on the cylinder 31 will be taken by the pins 3 and transferred to the cylinder 30, and thus become associated with the second sheet. When sheets are not to be associated, 125 the pins 80 will be secured in their retracted position, and the pins 3^a will be rendered operative.

The organization shown in Figs. 12 and 13 is substantially the same as that just described, except that an extra cylinder, 40, is provided to co-operate with the cylinder 30

to form the sheet-severing mechanism. In this case the pins 80 on the cylinder 31 are operated in the manner just described by means of a cam, *w*, upon the cylinder 30. The pins 3^a, however, are not rendered inoperative when sheets are to be associated. The first sheet will be taken by the pins 3^a and carried forward upon the cylinder 30 until its leading end is at the cylinder 31, at which time the stud of the arm 43 of the shaft upon which these pins are mounted will come into engagement with a cam, 26, (see Figs. 11 and 13,) by which the shaft will be rocked, so as to retract the pins and allow the sheet to be taken by the pins 80 and carried around upon the cylinder 31. The cam 26 is pivoted upon a stud, 71, in such manner that as the stud of the arm 43 passes the pivotal point of the cam it will bear upon the tail-piece 27 of the cam, and thereby rock the cam to the position shown by dotted lines in Fig. 11, so that as the pins 3 arrive at the cylinder 31 the stud of the arm 43 of their shaft will not be engaged by the cam, and these pins as a consequence will not be retracted. As the cylinder 31 completes its revolution, the pins 80 will be retracted by the cam *w*, and the pins 3, not being retracted by the cam 26, will take the sheet from the cylinder 31 and associate it with the second sheet upon the cylinder 30. As the stud of the arm 43 of the shaft carrying the pins 3 passes the cam 26, it will engage the tail-piece 27 and rock the cam 26 back to its original position, so that it will operate to retract the pins 3^a and allow the third sheet to be taken by the pins 80. When the sheets are not to be associated, the cam 26 will be moved outward by the stud 71, so as to be out of the path of the stud of the arm 43, as shown in Fig. 13, and the pins 80 will be secured in their retracted position.

It is to be remarked that the transverse severing mechanism, instead of being wholly or partly carried by the cylinders 30 31, as shown, may be carried by an independent pair of cylinders, and in such case the severing mechanism may be arranged to sever the web or webs into sheets before it or they are longitudinally folded. In case this is done suitable tapes must of course be provided to convey the sheets to the transverse folding mechanism.

The forms of transverse folding and associating mechanisms shown are deemed sufficient to illustrate the principle of the invention; but other forms of mechanism may be employed for these purposes; or one or both of these mechanisms may be entirely omitted and yet preserve certain features of the invention.

In regard to the collecting mechanism for collecting the sheets into lots when they are to be delivered without being folded transversely, it is to be remarked that, although the form of mechanism for this purpose which is herein shown is regarded as, all things considered, the best for the purpose, any other

form of mechanism may be used for this purpose and yet preserve the principle features of the present invention, and the same is to be remarked in regard to the sheet-piling mechanisms.

From the foregoing it will be seen that the present invention consists not so much in improvements in the individual mechanisms of which the whole delivery mechanism is composed, as in the combinations or organizations of the several mechanisms, whereby they are capacitated to produce certain results.

What I claim is—

1. The combination, with a longitudinal folder and a web-turner, of a web-severing mechanism which is capacitated to sever the web when in an unfolded condition, these three being so arranged that the web may be led either directly to the severing mechanism in an unfolded condition or to the folder and thence to the severing mechanism in a folded condition, all substantially as described.

2. The combination, with a longitudinal folder, a web-turner, and a web-severing mechanism, of a transverse folding mechanism, as the cylinder 30 and its auxiliaries, which is capacitated to act upon the sheets severed before they are longitudinally folded, these four being so arranged that the web or sheets may be led either directly to the transverse folding mechanism before being folded longitudinally or to the longitudinal folder and thence to the transverse folder after being longitudinally folded, all substantially as described.

3. The combination, with the turning-bars 10 12, arranged to turn and associate the webs *a b*, of a longitudinal folder, as 20 or 21, for folding said associated webs, and a web-severing mechanism arranged parallel with the printing-cylinders for severing the associated and folded webs into sheets, all substantially as described.

4. The combination, with the turning-bars 10 12, arranged to turn and associate the webs *a b*, of a longitudinal folder, as 20 or 21, for folding said associated webs, and web-severing and transverse folding mechanisms arranged parallel with the printing-cylinders for severing the associated and folded webs into sheets and folding the sheets, all substantially as described.

5. The combination, with the turning-bars 10 12, arranged to turn and associate the webs *a b*, of a longitudinal folder, as 20 or 21, for folding said associated webs, and web-severing and sheet-associating mechanisms arranged parallel with the printing-cylinders for severing the associated and folded webs into sheets and associating the sheets, all substantially as described.

6. The combination, with the turning-bars 10 12, arranged to turn and associate the webs *a b*, of a longitudinal folder, as 20 or 21, for folding said associated webs, and web-severing, sheet-associating, and transverse folding mechanisms arranged parallel with the printing-cylinders for severing the associated and

folded webs into sheets and associating and folding the sheets, all substantially as described.

7. The combination, with a plurality of longitudinal folders, of web turning and associating mechanism arranged to turn a plurality of webs which are running side by side, so as to change their direction of travel and bring them into line, whereby the webs may be led to different folders to be folded separately or associated and led to the same folder to be folded together, all substantially as described.

8. The combination, with the cutting-cylinders 30 31, adapted to receive and sever the full-width web, and arranged so that the web may be led directly to them, of a slitter, as 49, for dividing the web longitudinally into narrow webs, longitudinal folders, as 20 21, and turning-bars, as 10 12, which are arranged to operate upon the narrow webs before they enter the cutting-cylinders, whereby the narrow webs may be longitudinally folded and severed into sheets or be severed into sheets without being so folded, substantially as described.

9. The combination, with the cutting-cylinders 30 31, adapted to receive and sever the full-width web and arranged so that the web may be led directly to them, of a slitter, as 49, for dividing the web longitudinally into narrow webs, a longitudinal folder, as 20 or 21, and turning-bars 10 12, which are arranged to operate upon the narrow webs before they enter the cutting-cylinders, whereby the narrow webs may be associated and longitudinally folded and severed into sheets or be severed into sheets without being so associated and folded, substantially as described.

10. The combination, with a transverse folding mechanism, as the cylinder 30 and its auxiliaries, which is capacitated to act upon the sheets without their being folded longitudinally, of a slitter for dividing the web into narrow webs, longitudinal folders for folding the narrow webs, a web-turning mechanism, and a transverse severing mechanism, these devices or mechanisms being so arranged that the webs may be led either directly to the transverse folding mechanism without being folded longitudinally or to the longitudinal folders and thence to the transverse folder after being longitudinally folded, all substantially as described.

11. The combination, with a transverse folding mechanism which is capacitated to act upon the sheets without their being longitudinally folded, of a slitter for dividing the web into narrow webs, a web turning and associating mechanism for associating the narrow webs, a longitudinal folder for folding the associated webs, and a transverse severing mechanism, these devices or mechanisms being so arranged that the webs may be led either directly to the transverse folder without being folded longitudinally or to the web associating and longitudinal folding mechanisms and

thence to the transverse folder, all substantially as described.

12. The combination, with cutting-cylinders which are arranged parallel with the printing-cylinders and so that the web may be led directly thereto, and which are adapted to receive and sever the full-width web, of a longitudinal folder, as 20 or 21, and a turning-bar, which folder and bar are arranged to operate upon the web before it arrives at the cutting-cylinders, whereby the web may be longitudinally folded and then severed into sheets without being so folded, substantially as described.

13. The combination, with a transverse severing and folding mechanism adapted to operate upon and sever the full-width web and arranged so that the web may be led directly thereto, of a longitudinal folder, as 20 or 21, and a turning-bar, which are arranged to operate upon the web before it arrives at the transverse cutting and folding mechanism, whereby the web may be longitudinally folded and then severed into sheets and folded transversely or be severed into sheets and folded transversely without being longitudinally folded, substantially as described.

14. The combination, with a transverse severing and folding mechanism adapted to operate upon the full-width web and arranged so that the web may be led directly thereto, of a slitter, as 49, for dividing the web longitudinally into narrow webs, a longitudinal folder, as 20 or 21, and turning-bars, as 10 12, which folder and bars are arranged to operate upon the narrow webs before they arrive at the transverse severing and folding mechanism, whereby the web may be divided into narrow webs and the narrow webs associated and longitudinally folded and severed into sheets or be severed into sheets without being so associated and folded, substantially as described.

15. The combination, with a transverse severing and folding mechanism adapted to receive and sever the full-width web, and arranged so that the web may be led directly thereto, of a slitter, as 49, for dividing the web longitudinally into narrow webs, longitudinal folders, as 20 21, and turning-bars, as 10 12, which are arranged to operate upon the narrow webs before they arrive at the transverse severing and folding mechanism, whereby the web may be divided into narrow webs and the narrow webs longitudinally folded and severed into sheets or be severed into sheets without being so folded, substantially as described.

16. The combination, with the folding-cylinder 30 and a piling mechanism, as the carrier 32, for piling the sheets folded off said cylinder, of a sheet-collecting mechanism for receiving the sheets from said cylinder without their being folded thereby, and collecting them into lots, and a piling mechanism, as the fly 61, for piling the lots of sheets from the

collecting mechanism, whereby the sheets may be folded off the cylinder and delivered by one piling mechanism or be collected off the cylinder without being folded thereby and delivered by another piling mechanism, all substantially as described.

17. The combination, with the cutting and folding cylinders 30 31 and a piling mechanism, as the carrier 32, for piling the sheets 10 folded thereby, of a sheet-collecting mechanism for receiving the sheets from said cylinders without their being folded thereby and collecting them into lots, and a piling mechanism for piling the lots of sheets from the collecting mechanism, whereby the sheets may be folded off the cylinder and delivered by one piling mechanism or be collected off the cylinder without being folded thereby and delivered by another piling mechanism, all substantially as described.

18. The combination, with the cylinders 30 31, provided with auxiliary devices for folding and for associating and folding sheets, and a piling mechanism, as the carrier 32, for piling 15 the sheets folded thereby, of a sheet-collecting mechanism for receiving the sheets from said cylinders without their being folded thereby and collecting them into lots, and a piling mechanism for piling the lots of sheets from 20 the collecting mechanism, whereby the sheets may be folded off the cylinder or associated and folded off the cylinder and delivered by one piling mechanism or be collected off the cylinder without being folded thereby and delivered by another piling mechanism, all substantially as described.

19. The combination, with the cylinders 30

31, provided with sheet associating and folding devices, of a sheet-collecting mechanism, as the cylinder 60, and means for rendering 40 said folding and associating devices inoperative, all substantially as described.

20. The collecting - cylinder 60, provided with means for collecting sheets upon its surface and made capable of contracting as the 45 sheets accumulate upon it, all substantially as described.

21. The combination, with the collecting-cylinder 60, of the yielding pieces *c* and the guides for holding the sheets onto the cylinder, all 50 substantially as described.

22. The combination, with the collecting-cylinder 60, made capable of contracting as the sheets accumulate upon it, of the guides for holding the sheets onto the cylinder, all 55 substantially as described.

23. The combination, with the collecting-cylinder 60, having the yielding pieces *c*, of the stripper-fingers *n*, for directing the lot of sheets off the cylinder, all substantially as de- 60 scribed.

24. The combination, with a collecting-cylinder, as 60, of the segmental rolls 69 70, for receiving the lots of sheets as they are delivered from the cylinder, all substantially as 65 described.

In testimony whereof I have hereunto set my hand in the presence of two subscribing witnesses.

LUTHER C. CROWELL.
